E. E. REED

DOOR OPENING DEVICE

Filed May 20, 1924

E. E. Reed,
Inventor

By *Clarence A. St. Brian*,
Attorney

UNITED STATES PATENT OFFICE.

EZRA E. REED, OF SUNDANCE, WYOMING.

DOOR-OPENING DEVICE.

Application filed May 20, 1924. Serial No. 714,640.

To all whom it may concern:

Be it known that I, EZRA E. REED, a citizen of the United States, residing at Sundance, in the county of Crook and State of Wyoming, have invented certain new and useful Improvements in Door-Opening Devices, of which the following is a specification.

This invention relates to new and useful improvements in attachments for doors, and has for its principal object to provide a means for releasing the latch from locked engagement with the keeper, whereby the door may be opened by the foot of a person whose hands are occupied.

One of the important objects of the invention is to provide a foot controlled door opening device of the above mentioned character, which may be easily and readily placed in position on any door and fastened to the latch therefor.

A further object of the invention is to provide a door opening device of the above mentioned character, which is simple in construction, inexpensive, strong and durable, and further well adapted for the purposes for which it is designated.

Other objects and advantages of this invention will become apparent during the course of the following detailed description.

In the accompanying drawing, forming a part of the specification, and in which like numerals designate like parts throughout the same:

Figure 1 is a side elevation of my improved invention, showing the same in position on a door.

Figure 2 is a sectional view, taken approximately on the line 2—2 of Figure 1.

Figure 3 is a similar view, taken approximately on the line 3—3 of Figure 1.

Figure 4 is a side elevation of the crank lever supported on the upper end of the operating rod.

Figure 5 is a sectional view, taken approximately on the line 5—5 of Figure 3.

Figure 6 is a bottom plan view of a door, showing a toe plate mounted thereon, and

Figure 7 is a modification of a door latch engaging means.

In the drawing, wherein for the purpose of illustration is shown the preferred embodiment of my invention, the numeral 1 designates a door, which is preferably of the swinging type, and is provided with the

usual door latch 2, and the door knob 3 therefor. My door opening device comprises an elongated vertical rod 4, which is supported in the upper and lower brackets 5 and 6 respectively, the latter being secured to the door on one side thereof, in any suitable manner. The rod 4 is supported in the bracket, and is adapted for rotatable movement therein, in the manner to be described presently.

Supported on the upper end of the rod 4 is the crank lever 7, and the same is provided with a suitable socket 8, for receiving the upper end of the rod, and the socket member is provided with the clamping means 9, for securing the socket member in position on the upper end of the rod, it being understood that the socket member is flexed, so as to enable the clamping means 9 to properly function.

The laterally extending portion of the crank lever 7 is provided with an opening 10, in which is received an end of the horizontally disposed rod 11, and the opposite end of the rod 11 is provided with a hook 12 for engagement with the arm portion 13 of the clamping member designated generally by the numeral 14.

The clamping member 14 is adapted to extend around the knob 3 and the latch 2 and comprises the complementary sections 15 and 16 respectively, the section 15 being provided with a suitable opening 17, for receiving the inner curved end 18 of the section 16. This construction provides what may be termed as a hinged joint, and the free ends of the section are disposed outwardly in parallel spaced relation and receive therebetween the clamping bolt and nut 19, in the manner clearly shown in Figure 5 of the drawing. The clamping member 14 is adapted to be secured to the knob 3, which is rigidly supported on the spindle of the lock or bolt 2, in such a manner as to operate the latch to release the same from engagement with its keepers, when the rod 11 is actuated by the crank lever 7, in a manner to be hereinafter more fully described.

For the purpose of actuating the vertical rod 4 and the clamping member 14, which is connected to the knob on the left, I provide the lower end of the vertical rod 4, below the bracket 6, with the foot engaging lever 20. The foot engaging lever is clamped around

the lower end of the rod and is rigidly secured thereto so as to cause the rotation of the rod, when the foot lever is actuated. In Figure 2 of the drawing, the foot lever is 5 more clearly illustrated and the same is shown in its normal inoperative position.

The operation of the door operating device may be briefly stated as follows: Normally the door is in a closed position, and 10 when a person desires to open the same and the hands are occupied so that he cannot have access to the knob with his hands, he presses inwardly on the foot lever 11, causing the vertical rod 4 to rotate in the brackets 15 5 and 6, and simultaneously causing the crank lever 7 to actuate the horizontally disposed rod 11 and the clamping member 14 connected thereto and extending around the knob, so as to cause the clamping member 20 to disengage the latch from its keeper, whereby the door may be swung to an open position. To facilitate the swinging of the door to an open position, the toe plate 21 is provided, and the same is of such a construction 25 as to enable a person to either press inwardly on the toe plate, or place his toe between the plate and the door, in order to exert a pull on the door, so that the same may be opened.

30 In Figure 7 of the drawing, a modification is shown, wherein the door is provided with a thumb latch 22, and the knob 23 therefor, and as the same is of the well known construction, a further detailed description of 35 the same is not thought necessary. For opening a door provided with a latch of this construction, I provide the same operating means as heretofore set forth, with the exception that instead of the clamping member 14, which engages the knob, I provide the bell crank lever 24 which is pivoted at 40 25 to the door, and has one end thereof slotted to engage the knob 23 of the thumb lock, while the opposite end is provided with 45 an eye 26, for engagement with the hooked end of the horizontally disposed rod 11. The operation in releasing the thumb nut,

however, is identical with that heretofore described.

It will thus be seen from the foregoing description, that a door opening device has been provided, which is simple in construction, inexpensive, and the parts are so arranged as to enable the same to be readily and easily actuated by the foot of a person, 50 when a person's hands are occupied. An attachment of this character may be placed upon screen doors or other doors, without necessitating the alteration of the door, in installing the attachment in position thereon, and furthermore the device will be 55 strong and durable.

While I have shown the preferred embodiment of my invention, it is to be understood that various changes in the size, shape, 60 and arrangement of parts, may be made, without departing from the spirit of the invention and the scope of the appended claims.

Having thus described my invention, what 70 I claim is:

1. In combination with a swinging door and a latch therefor, of means for releasing said latch from a locked position, comprising a vertical rod rotatably supported on 75 said door, a crank lever detachably supported on the upper end of said rod, a connection between said crank lever and the knob of said latch, and a foot actuated lever on the lower end of the vertical rod.

2. In combination with a swinging door and a latch therefor, of means for releasing the latch from a locked position, comprising a vertical rod rotatably supported on said door, a crank lever detachably supported on 85 the upper end of said rod, a clamping member for the knob of said latch, a connection between said clamping member and said crank lever, said clamping member comprising a pair of complementary sections detachably engaged with said knob, and a foot actuated lever on the lower end of said rod.

In testimony whereof I affix my signature.

EZRA E. REED.
